UNITED STATES PATENT OFFICE.

JOHN W. LINDQUIST, OF GALESBURG, ILLINOIS, ASSIGNOR TO HIMSELF AND FRED LINDQUIST, OF SAME PLACE.

TONGUE-SUPPORT.

SPECIFICATION forming part of Letters Patent No. 515,476, dated February 27, 1894.

Application filed April 3, 1893. Serial No. 468,818. (No model.)

To all whom it may concern:

Be it known that I, JOHN W. LINDQUIST, a citizen of the United States, residing in Galesburg, in the county of Knox and State of Illinois, have invented a new and useful Improvement in Spring Wagon-Tongue Supports, of which the following is a specification.

My invention relates to spring supports for wagon or other vehicle tongues.

10 The object of my invention is to provide a wagon tongue support of a simple, efficient and durable construction, that may be cheaply manufactured and easily and conveniently applied, and which will operate to support the 15 tongue direct from the axle by a direct pulling strain thereon without causing any tilting, prying or other strain upon the hounds, reach or other parts.

To this end my invention consists, in connection with the wagon axle and tongue, in the combination of one or more, preferably two, pulling bars attached to the axle and a spring pivotally connected to said pulling bars, and provided with a hook or loop bearing against the tongue and another hook or loop bearing against the draw bolt of the hounds; so that the weight of the tongue is supported directly from the axle by a pulling strain thereon communicated through the 30 pulling bars to which the spring is pivoted. The spring is, preferably, made double, that is to say with two coils, the two coils being however made out of one single piece or steel rod.

35 In the accompanying drawings, which form a part of this specification, and in which similar letters of reference indicate like parts, Figure 1 is a plan view of a device embodying my invention. Fig. 2 is a vertical section on line 2 2 of Fig. 1. Fig. 3 is a detail perspective view of the double coil spring and Fig. 4 is a like perspective view of the pulling bars which embrace or are hooked to the axle.

45 In the drawings A represents a wagon or other vehicle axle, or a portion thereof.

B is the tongue, C the hounds, D the draw bolt by which the tongue is pivotally connected to the hounds, and E the bolster.

50 F F are the pulling bars which are connected to the axle A, preferably by hooks or

loops f formed integral with the bars F and adapted to hook under or over and embrace the axle.

G is the spring, the same being preferably 55 a spiral or coil spring, and preferably furnished with two coils g g. The spring G has a loop or hook portion or arm g' that bears against the tongue, and a hook or loop portion or arm g² that bears against the draw bolt 60 D. Each coil g also has an eye or central opening g³ to receive the pivot bolt f' by which the spring is pivotally connected to the pulling bars F. The pivot bolt f' has a head f² and nut f³. The loop portion g' of the spring 65 that fits under and bears against the tongue is formed by the middle portion of the spring G, and the two hooks g² that hook around the draw bolt D are formed at the two extremities of the rod forming the spring. 70

The two coils g g of the spring G fit, one on one side of the tongue and the other on the other side thereof; and the loop g' extends transversely across the tongue. The two vertical sides of the tongue thus in a measure 75 act as guides to keep the spring in position in connection with the sides of the pulling bars F F and the head f² and nut f³ of the bolt f'. By this means it will be observed that the tongue is given a spring support without putting any prying or lever strain upon the hounds, reach or other parts of the wagon; and the tongue is supported directly from the axle by a pulling strain thereon communicated thereto through the pulling bars F F. This 85 will be readily understood by reference to Fig. 2, from which it will be seen that the tongue rests upon and is supported by one arm or end g' of the spring, while the other arm or end g² of the spring rests against the draw 90 bolt D, and the pivot g³ of the spring is pivotally connected to the pulling bars F.

The pulling bars F are preferably furnished with a number of holes f⁴ for the pivot bolt f' to pass through to adjust the normal height 95 of the tongue, or the tension of the spring, as may be required from time to time. By employing a double coil spring, one coil fitting on each side of the tongue and the whole made out of a single rod or bar, the spring is made self 100 sustaining, so that its coils naturally tend to remain in vertical planes or in position for

proper operation; and the accomplishment of this result is also aided by employing double pulling bars F F, one on each side.

I claim—

- 5 1. A spring support for a wagon or vehicle tongue, consisting in the combination of a pulling bar adapted to be attached to the axle, and a spring pivotally connected to said pulling bar having one arm fitting against the tongue and another arm fitting against the draw bolt of the tongue, substantially as specified.
- 10 2. The vehicle tongue support, consisting in the combination of draw bars F F having loops or hooks f f for connecting with the axle, a double coil spring G made of a single piece or rod having eyes g³ g³ pivotally connected to said pulling bars, hooked arms g² g² adapted to connect with the draw bolt, and arm or loop 15 g' adapted to bear against the tongue, substantially as specified.
- 20 3. The combination of axle A, with tongue C and draw bolt D, of hooked pulling bars F F connected to the axle, double coil spring G having two coils g g, one fitting on each side 25 of the main bar of the tongue and furnished with eyes g³ g³, a pivot bolt f' passing through

said pulling bars and the eyes of said coils, said spring G having also a looped middle portion g' fitting against the tongue, and 30 hooked arms g² g² fitting against said draw bolt D substantially as specified.

4. A spring support for a wagon or vehicle tongue, consisting in the combination of a pair of pulling bars F F connected to the axle, 35 and a coil spring pivotally connected to said pulling bars and having two arms, one bearing against the tongue to support the same and the other against the draw bolt of the tongue, substantially as specified. 40

5. A spring support for a wagon or vehicle tongue, consisting in the combination of a pulling bar adapted to be connected with the axle, and a double coil spring made in a single piece and pivotally connected to said pulling bars, said spring being provided with a loop portion g' bearing against the tongue, and a pair of hooks g² bearing against the draw bar of the tongue, substantially as specified. 45
